UNITED STATES PATENT OFFICE.

SIMON SEGAL, OF BOSTON, MASSACHUSETTS.

SHOE.

1,187,663.

Specification of Letters Patent. Patented June 20, 1916.

Application filed October 4, 1915. Serial No. 54,010.

To all whom it may concern:

Be it known that I, SIMON SEGAL, a citizen of the United States, residing at Boston, in the county of Suffolk and State of Massachusetts, have invented certain new and useful Improvements in Shoes; and I do declare the following to be a full, clear, and exact description of the invention, such as will enable others skilled in the art to which it appertains to make and use the same.

This invention relates generally to shoes and more particularly to a detachable upper for shoes.

The primary object of the invention is to provide an upper which can be detachably secured to the permanent upper of a low cut shoe, whereby to transform the latter into a high shoe, a low shoe with an ornamental edging around the top, and the like.

Another object of the invention is to provide a device which will be simple, strong, durable and inexpensive in construction, efficient and reliable in application, and well adapted to the purpose for which it is designed.

With these and other objects in view, the invention consists of certain novel features of construction, and the combination and arrangement of parts which will be herein-after fully described and claimed.

In the accompanying drawings:—Figure 1 is a side elevation of a low cut shoe constructed in accordance with this invention, showing a portion cut away to illustrate the fastening elements carried thereby; Fig. 2 is a similar view of an ornamental edging applied to a low cut shoe when the latter is to be worn as a commonly called "pump;"

Fig. 3 is a similar view showing the application of a detachable upper to an ordinary "pump" to transform the latter into a high shoe; Fig. 4 is a similar view showing the application of a detachable upper to an ordinary "pump" transforming the latter into

a low cut shoe of the commonly called "oxford" type, a portion of the shoe being cut away to illustrate a modified form of fastening element carried by the shoe; Fig. 5 is a sectional view taken on the line 5—5 of Fig.

50 3; Fig. 6 is an enlarged detail perspective view of one of the hooks carried by the detachable upper; and Fig. 7 is an inner face view of a portion of the detachable upper showing the arrangement of the hooks thereon.

Referring more particularly to the draw-

ings, 1 represents the permanent upper of a low cut shoe. Disposed between the outer covering 2 and the lining 3 of the permanent upper 1 along the top edge of the latter, is a series of metal plates 4, said plates 4 extending completely around the upper and each having its ends contacting with the adjacent ones. The plates 4 are provided with integral pins extending outwardly through apertures 6 in the outer covering 2 of the upper 1, said pins 5 having heads 7 at their outer ends for a purpose to be described.

In Fig. 2 of the drawings a detachable upper in the form of an ornamental edging 8 is shown applied to the type of low cut shoe illustrated in Fig. 1, whereby the shoe may be worn as a commonly called "pump". This edging 8 hides the pins 5 from view and gives the shoe a finished and neat appearance. Arranged on the inner side of the edging 8 along its lower edge is a series of hooks 9, the latter being substantially U-shaped in construction and having their open sides disposed upwardly, the arms 10 thereof being provided on their inner edges with shoulders 11. Carried by the hooks 9 are apertured ears 12 through which pass a thread 13 or any other suitable element for securing said hooks to the edging 8. These hooks 9 are adapted to coöperate with the pins 5 carried by the permanent upper 1, whereby to detachably connect the edging 8 to the latter, the pins 5 being forced beyond the shoulders 11 on the arms 10 of the hooks 9 and held locked by the resiliency of said arms, and the heads 7 of the pins 5 being disposed between the arms 10 and the inner side of the edging 8.

In Figs. 3 and 4 the hooks 9 are shown secured to detachable uppers 14 to transform an ordinary "pump" type of low cut shoe into respectively a high shoe and an "oxford" type of low shoe.

The longitudinal axes of the hooks 9 are arranged perpendicular to the lower edge of the detachable upper or edging 8 with the exception of the foremost ones which are disposed obliquely, as clearly illustrated in Fig. 7 of the drawings. This arrangement, in addition to holding the edging down in proper position, also provides a means for pulling the same forwardly to prevent wrinkles and unevenness.

Instead of mounting each pin 5 on an independent plate 4 as herein before described, the former may be carried by a continuous

strip of metal 15 as shown in Fig. 4. This strip 15 also acts as a reinforcement for the upper edge of the permanent upper 1.

Although the invention is shown applied to an ordinary "pump", it can be equally applied to any style of shoe, and may be used to attach uppers of various materials and colors as well as style and shape.

Various changes in form and proportion may be resorted to without departing from the spirit of this invention, and hence I do not wish to be limited to the construction herein described other than set forth in the appended claims.

15 I claim:—

1. The combination with a shoe having a permanent upper composed of an outer covering and a lining, said covering having apertures therein along the upper edge thereof, a series of metal plates disposed between said covering and said lining and extending completely around said upper, said plates being disposed along the upper edge of the latter and each contacting with the adjacent ones, and headed pins extending outwardly from said plates through said apertures, of a removable upper having a series of U-

shaped hooks arranged along its lower edge and secured to the inner side thereof, the open sides of said hooks being disposed upwardly for co-operation with said pins.

2. The combination with a shoe having a permanent upper, and a series of headed pins projecting outwardly from said upper, said pins being arranged along the upper edge of the latter, of a removable upper having a plurality of U-shaped hooks arranged along its lower edge and secured to the inner side thereof, the open sides of said hooks being disposed upwardly for co-operation with said pins, the longitudinal axes of the foremost hooks being disposed obliquely to the lower edge of the detachable upper, and the longitudinal axes of the others being perpendicular to the lower edge of the detachable upper.

In testimony whereof I have hereunto set my hand in presence of two subscribing witnesses.

SIMON SEGAL.
